UNITED STATES PATENT OFFICE.

NEWTON ALLEN, OF LYONS, OREGON.

SAW-GAGE.

1,345,339.

Specification of Letters Patent.

Patented July 6, 1920.

Application filed January 3, 1919. Serial No. 269,394.

To all whom it may concern:

Be it known that I, NEWTON ALLEN, citizen of the United States, residing at Lyons, in the county of Linn and State of Oregon, 5 have invented certain new and useful Improvements in Saw-Gages, of which the following is a specification.

This invention relates to metal tools and implements, and more especially to dressing 10 and jointing saws; and the object of the same is to produce a tool by which the teeth of ordinary cross cut saws can be gaged and jointed.

The invention includes means for adjusting the block through which the raker teeth project so that the tips of the same can be filed off to the desired relative length with respect to the other teeth.

The invention also includes a file clamp, 20 for a purpose yet to appear.

Details are set forth in the following specification and claim.

Referring to the drawings

Figure 1 is a front elevation

25 Fig. 2 is a rear elevation, and

Fig. 3 is a vertical section on the line 3—3 of Fig. 2.

Fig. 4 is a vertical section on the line 4—4 of Fig. 1.

30 The body 11 has openings 11' for the sake of lightness and through which the fingers may be passed, and is provided along the upper edge of its front face with a flange 1 and along its rear face with two flanges 2 and 3. A portion of flange 1 is cut away as indicated at 5 and the cut extends down into the body 11 so as to produce a large opening. Within the opening moves a block 6 having an opening or slot 7 for the

40 reception of the raker teeth R shown in dotted lines in Fig. 1 when the ordinary teeth T of the saw S underly the flange 1. Screws 8 are threaded upward in the body 1 and their unthreaded and headed upper ends 9 are rotatably mounted within sleeves 9' carried by the block 6, and by turning these screws simultaneously in the same direction the position of the block within the recess or opening 5 may be very accurately 45 adjusted so that its upper face will almost exactly aline with the lower face of the flange 1. The use of the device as a saw gage is indicated in Fig. 1 and well known to those familiar with this art. A striking

feature of my improvement is the provision of indicating marks 20 and 21 in the ends of the opening 5, as best seen in Fig. 4, one set of these marks being graduated to one-eighth inch and the other to one-sixteenth inch. The marks are visible above the block 6 when the latter is adjusted by the screws 8, and are provided for the purpose of permitting the operator to tell with accuracy to just what position this block is adjusted and therefore, how much of the tips of the raker 65 teeth should be filed off.

On the back of the body 11 is mounted a jaw 10, the upper portion of the jaw 10 being open as indicated at 12 for the reception of pin 13 whose stem is threaded in the body 70 and whose head constitutes a nut as shown at 14 in Fig. 3. The body of the jaw has an upright groove 15 in which lies screw 16 threaded upward through the nut 14, and the head 17 of the screw underlying the 75 lower end of the jaw and the other end of the screw underlying the top of the open portion of frame 12. Therefore, by turning the screw the entire jaw can be raised or lowered within the opening 4 through 80 the two flanges 2 and 3. Coacting with the upper end which is the active face of this jaw, are two studs, 18 and 19, inserted in the body 11 of the tool and preferably near the ends thereof. The use of this device is 85 well known to those familiar with the art. A file F is indicated in dotted lines as clamped beneath the studs and above the jaw when the latter is adjusted by turning the screw. This file is for jointing the saw 90 teeth as is understood.

The foregoing description and the drawings have reference to what may be considered the preferred, or approved form of my invention. It is to be understood that I may make such changes in construction and arrangement and combination of parts, materials, dimensions, et cetera, as may prove expedient and fall within the scope of the appended claim.

Having thus fully described my invention what I claim as new and desire to secure by Letters Patent is:—

In a device of the character described, the combination of a body having an elongated opening extending thereinto from its upper edge, a block extending longitudinally of said opening, screws threaded

through the body and extending into said opening, whereby the screws will not be exposed upon either side of the body and will thus be protected from injury, said screws 5 having heads upon their upper ends, sleeves surrounding the screws contiguous to said heads and being carried by said block, whereby as the screws are rotated, said block

may be moved within said opening as desired.

In testimony whereof I affix my signature in presence of two witnesses.

NEWTON ALLEN.
